UNITED STATES PATENT OFFICE.

FRANK DITCHFIELD, OF MONTREAL, QUEBEC, CANADA.

BOLSTER.

1,123,257.

Specification of Letters Patent.

Patented Jan. 5, 1915.

Application filed April 10, 1914. Serial No. 830,932.

To all whom it may concern:

Be it known that I, FRANK DITCHFIELD, a citizen of the Dominion of Canada, and resident of the city of Montreal, in the Province of Quebec and Dominion of Canada, have invented new and useful Improvements in Bolsters, of which the following is a full, clear, and exact description.

This invention relates to improvements in bolsters, and the object is to provide a bolster using rail sections for the compression and tension members.

A further object is to provide a bolster so arranged that accuracy of dimension in certain directions is not necessary in order that worn rails may be used.

A still further object is to provide a bolster using rail sections for tension and compression members, in which the stress of the tension member is accurately centered on the compression members.

Another object is to provide a bolster structure having the minimum depth at the ends.

Still another object is to provide a bolster comprising a minimum number of parts connected by a minimum number of rivets.

At the present time, all railroads suffer considerable loss in the disposal of worn rails. The difference between the price of worn rails as scrap and new rails is out of all proportion to the loss of metal from wear and the cost of reworking, so that the question of economically using or disposing of worn rails has always been a problem of considerable magnitude. Even with the constant use of old rails for sidings and the like and for miscellaneous purposes, there still remains a large number of rails which must be disposed of at great loss. It is possible to re-roll worn rails to smaller section, but with the constantly increasing weight of rolling stock, the lighter rails have only a limited use, and there is in addition the cost of re-rolling.

The present invention aims both at providing a use for the worn rails and to provide a strong and durable bolster at very low cost. This is accomplished by using rail sections for the compression and tension members of the bolster. The compression and tension members are connected together by suitable castings secured in place by a minimum number of rivets. In order to obtain a minimum depth at the bolster ends,

the tension member is deformed to eliminate the web, and looped over the end casting, which is designed to center the stress of the tension member directly on the end of the compression members, so that there is nothing beyond a compression stress in the end castings.

In the drawings which illustrate the invention:—Figure 1 is a side elevation. Fig. 2 is a vertical longitudinal section at the center of the bolster. Fig. 3 is a plan view. Fig. 4 is an outer end elevation. Fig. 5 shows on the left an inner end elevation of the end casting, and on the right, a section of the end casting on the line 5—5, Fig. 1. Fig. 6 is a vertical transverse section at the center of the bolster.

Referring more particularly to the drawings, 11 designates the compression and 12 the tension members of a bolster, each of which is formed of inverted rail sections. The compression member 11 is preferably formed of two spaced rail sections, and the tension member of a single rail section, located centrally under the space between the compression members and having its ends passing between the ends of the compression members.

The strut 13 at the center of the bolster is of substantially the usual form, having its upper end shaped in conformity with the sides of the compression members, and provided with an aperture 14 for a king pin. The lower end of the strut is flanged at 15 to hold the base of the tension member 90 against displacement. This strut is rigidly connected to the compression member by rivets 16 which members are in turn connected to one another by being riveted to the center plate 17. The center plate is 95 provided with side flanges 18 which embrace opposite sides of the compression members and hold the same against lateral displacement.

The compression members 11 are offset intermediate the center and ends, so that the end portions are parallel with the center portion, but in a different plane. The tension member is bent upwardly from the strut and passes between the end portions of the 105 compression members. In order to reduce the depth of the bolster at the ends, the ends of the tension member are deformed, so that the web of the rail section disappears, being absorbed in the head which is driven down 110

and becomes attached directly to the base. The metal of the web may be disposed either by enlarging the head, widening and thickening the base, or both combined.

5 The end castings 19 which connect the compression and tension members are box-like in form having a solid top plate 20 and suitably shaped bottom plate 21, side plates 22 and an outer end plate 23 suitably apertured for the passage of the tension member. Within the end casting and formed integral with the sides thereof are ribs 24 which conform to the shape of the compression members, fitting snugly between the base and head, and against the web of each. Between the compression members, the bottom plate of the end casting is provided with a pair of ribs 25 between which the head of the tension member passes. The upper edges 20 of these ribs are suitably inclined and support the base of the tension member, which passes out of the casting through the aperture 26 in the outer end plate 23 thereof. An inclined lip 27 is provided at the junction of the outer end and top plates, parallel with the sloping upper edges of the ribs 25. The extreme end of the tension member which may be suitably tapered is bent over this lip in U-shape and secured by rivets 28. The pull of the tension member on this lip is communicated to the compression members by means of two heavy ribs 29 at the ends of the lip, located exactly in line with the webs of the compression members. This arrangement relieves the end casting of all bending or twisting stresses, the pull of the tension member being exerted directly against the ends of the compression members, the end casting being held in compression between the members.

The inner end of the casting is open for the insertion of the compression and tension members. Closure of this end is effected by a wedge-shaped filler 30, which is inserted after the compression and tension members are in place. This filler bears upwardly against the top plate and downwardly against the base of the tension member holding the same securely down on the ribs 25. In addition, the filler is shaped at the ends to fit snugly between the head and base, and against the web of each compression member, so that these members are held against movement toward one another.

45 50 55 60 65 The filler is secured in place by means of rivets 31 passing through the compression members and side plates of the end casting and by a rivet 32 passing through the top plate of the casting.

60 The method of making the bolsters is extremely simple. After the compression and tension members have been completely formed, with the exception of the loop on the ends of the tension member, the compression and tension members and strut are

assembled, and the end castings slipped on until the outer end plates 23 abut the ends of the compression members. The projecting ends of the tension member which have been previously heated are then bent over the lip of the end casting. As the tension member cools, the metal contracts and draws the tension and compression members and end castings very tightly together. The tension member and lips are then drilled, 70 and the rivets 28 inserted. Finally, the wedge-shaped filler 30 is inserted and driven up tightly between the top plate 20 and base of the tension member, and secured in position by the rivets 31 and 32.

80 From the foregoing description, and the drawings, it will be readily seen that the only bearing between the rail sections and castings is on the base web and underside of the head of the rail sections, where no 85 wear occurs and where the variation in size is practically negligible. The top of the base and underside of the head are converging surfaces, and as the parts of the castings engaging these surfaces are similarly tapered, 90 it is obvious that satisfactorily tight fits may be obtained. The treads of the rail sections do not come into contact with the castings, and are in no way used as bearing surfaces, so that if apertures in the 95 castings are made to accommodate a new rail, any rail of the same section, no matter how badly worn, may be used with satisfactory results. The use of inverted rail sections 100 enables the perfect bearing to be obtained. The use of two spaced rail sections forming the compression member enables the tension member to be inserted between the same at the ends, so that the forces acting in the members are properly centralized 105 at the ends. The interdigitating arrangement of the members, combined with the reforming of the tension member ends, enables a very shallow end casting to be obtained which may be used on almost any 110 style of truck. In this connection, it will be understood that while the side and bottom plates of the end castings are shown plain, these may be formed in accordance with the design of truck or other apparatus in which 115 the bolster is used.

120 While the end members have been referred to as castings, it is obvious that they may be forgings or formed according to any other method.

Having thus described my invention, what I claim is:

1. A bolster having the compression and tension members formed of rail sections.
2. A bolster having the compression and tension members formed of inverted rail sections.
3. A bolster having the compression and tension members formed of rail sections interdigitating at the bolster ends.

4. In a bolster, a compression member composed of a plurality of substantially parallel portions, and a tension member straight between the center and ends of the compression member composed of parts one less in number than the compression member parts, the ends of said tension member passing between the portions of the compression member at the ends thereof, and an end member connecting the ends of the compression and tension members. 76
5. In a bolster, a compression member formed of a pair of rail sections spaced apart, a tension member of rail section, and end members connecting adjacent ends of said compression and tension members. 75
10. In a bolster, compression and tension members formed of rail sections, and end members embracing the ends of said compression and tension members, and forming a connection therebetween. 80
15. In a bolster, compression and tension members formed of rail sections, an end member embracing the ends of said compression and tension members and abutting the ends of the compression members. 85
20. In a bolster, compression and tension members formed of rail sections, an end member embracing the ends of said compression and tension members and abutting the ends of the compression members, and supporting means for the tension member arranged to direct the pull of the tension member centrally against the ends of the compression members. 90
25. In a bolster, compression and tension members formed of rail sections, an end member embracing the ends of said compression and tension members and abutting the ends of the compression members, a lip on said end member for the attachment of the tension member, and supporting ribs for said lip positioned to center the pull of the tension member against the ends of the compression members. 95
30. In a bolster, a pair of spaced compression members of inverted rail section, a tension member of inverted rail section having the ends thereof projecting between the compression members, and means directing the pull of the tension member centrally on the ends of the compression members. 100
35. In a bolster, spaced compression members of inverted rail section, a tension member of inverted rail section projecting at its ends between the ends of the compression members, an end member, and a lip thereon for the attachment of the tension member arranged to direct the pull of the tension member centrally against the ends of the compression members. 105
40. In a bolster, spaced compression members of inverted rail section, a tension member of inverted rail section, end members connecting the ends of said compression and tension members each comprising top and side plates holding the compression members against upward and outward movement, an end plate abutting the ends of the compression members, and a bottom plate having ribs thereon arranged to hold the tension member against downward and lateral movement. 110
45. In a bolster, spaced compression members of inverted rail section, a tension member of inverted rail section, end members connecting the ends of said compression and tension members, and a key inserted between the compression and tension members. 115
50. In a bolster, spaced compression members of inverted rail section, a tension member of inverted rail section, end members connecting the ends of said compression and tension members, and a key inserted between the compression and tension members. 120
55. In a bolster, spaced compression members of inverted rail section, a tension member of inverted rail section, end members connecting the ends of said compression and tension members, and a key inserted between the compression and tension members. 125
60. In a bolster, spaced compression members of inverted rail section, a tension member of inverted rail section, end members connecting the ends of said compression and tension members, and a key inserted between the compression and tension members. 130
65. In a bolster, a pair of compression members of inverted rail section, a tension member of inverted rail section, end members connecting the ends of said compression and tension members, and a key inserted between the compression and tension members. 135
70. In a bolster, compression members of inverted rail section, a tension member of rail section, an end member connecting the ends of the compression and tension members, and held in compression therebetween. 140
75. In a bolster, a pair of compression members of inverted rail section, a tension member of inverted rail section, end members connecting the ends of the compression and tension members, each comprising a top plate, side plates conforming to the contour of the compression members, and means for supporting the tension member between the compression members. 145
80. In a bolster, a pair of compression members of inverted rail section, a tension member of inverted rail section, end members connecting the ends of the compression and tension members and each comprising top and side plates following the contour of the compression members, an end plate apertured for the passage of the tension member, a ribbed bottom plate arranged to support the tension member, and a lip adjacent the aperture of the end plate over which the end of the tension member is bent. 150
85. In a bolster, a pair of compression members of inverted rail section, a tension member of inverted rail section, end members connecting the ends of the compression and tension members comprising top and side plates following the contour of the compression members, an end plate apertured for the passage of the tension member forming an abutment for the end of the compression members, a lip on said end plate for the attachment of the tension member, and supports for said lip directing the pull of the tension member to the portions of the end plate forming compression member abutments. 155
90. In a bolster, compression members of inverted rail section, a tension member of inverted rail section having its ends passing between the ends of the compression members, end members connecting the ends of the compression and tension members each comprising top and side plates holding the compression members against upward and outward movement, an end plate abutting the ends of the compression members, and a bottom plate having ribs thereon arranged to hold the tension member against downward and lateral movement. 160
95. In a bolster, compression members of inverted rail section, a tension member of inverted rail section, end members connecting the ends of said compression and tension members, and a key inserted between the compression and tension members. 165
100. In a bolster, compression members of inverted rail section, a tension member of inverted rail section, end members connecting the ends of said compression and tension members, and a key inserted between the compression and tension members. 170
105. In a bolster, compression members of inverted rail section, a tension member of inverted rail section, end members connecting the ends of said compression and tension members, and a key inserted between the compression and tension members. 175
110. In a bolster, compression members of inverted rail section, a tension member of inverted rail section, end members connecting the ends of said compression and tension members, and a key inserted between the compression and tension members. 180
115. In a bolster, compression members of inverted rail section, a tension member of inverted rail section, end members connecting the ends of said compression and tension members, and a key inserted between the compression and tension members. 185
120. In a bolster, compression members of inverted rail section, a tension member of inverted rail section, end members connecting the ends of said compression and tension members, and a key inserted between the compression and tension members. 190
125. In a bolster, compression members of inverted rail section, a tension member of inverted rail section, end members connecting the ends of said compression and tension members, and a key inserted between the compression and tension members. 195

- members and arranged to hold the same against movement relatively to one another and to the end member.
19. In a bolster, compression and tension members of inverted rail section, end members connecting the ends of said compression and tension members and each comprising top and side plates holding the compression members against upward and outward movement, a bottom plate holding the tension member against downward and lateral movement, and a key inserted between the compression and tension members holding the compression members against inward and downward movement and the tension member against upward movement.
20. In a bolster, a compression member formed of two substantially parallel parts, a tension member of greater depth than width inserted at its ends between the ends of the compression members, and having the inserted portion of its ends reduced in depth.
21. In a bolster, compression and tension members of inverted rail section, the ends of the tension member being of less depth than the central portion thereof.
22. In a bolster, compression and tension members of inverted rail section, the tension member having the web thereof eliminated and the head formed directly on the base.
23. In a bolster, compression and tension members of inverted rail section, the tension member having the web thereof eliminated and the base gradually widened at the ends, the head being formed directly on the base.
24. In a bolster, compression and tension members of inverted rail section, the tension member decreasing in depth and increasing in width at the ends.
25. In a bolster, a pair of compression

members of inverted rail section, a tension member of inverted rail section having the ends thereof inserted between the ends of the compression member and reduced in depth sufficiently to lie within the same plane as the ends of the compression members.

26. In a bolster, a pair of compression members of inverted rail section, a tension member of inverted rail section having the ends thereof inserted between the ends of the compression members and simultaneously decreased in depth and increased in width, and end members abutting the ends of the compression members and forming attaching means for the ends of the tension members.

27. In a bolster, a pair of compression members of inverted rail section, a tension member of inverted rail section, a strut separating compression and tension members at the center, end members connecting the ends of said compression and tension members, and a key within the end member holding the compression and tension members against relative movement.

28. In a bolster, a pair of compression members of inverted rail section, a tension member of inverted rail section, a strut separating said compression and tension members at their centers, end members apertured for the passage of the tension member ends and abutting the ends of the compression members, said tension members having the ends thereof bent over and attached to said end members.

In witness whereof, I have hereunto set my hand in the presence of two witnesses.

FRANK DITCHFIELD.
